UNITED STATES PATENT OFFICE.

LOUIS KRAJESKI, OF CHICAGO, ILLINOIS.

DESIGN FOR A TOY BANK.

No. 39,680.

Specification for Design.

Patented Nov. 3, 1908.

Application filed April 23, 1908. Serial No. 428,879. Term of patent 7 years.

To all whom it may concern:

Be it known that I, LOUIS KRAJESKI, a citizen of the United States, residing at Chicago, in the county of Cook and State of Illinois, have invented a new, original, and ornamental Design for Toy Banks; and I do hereby declare the following to be a specification of the same, reference being had to the accompanying drawing, forming a part thereof.

Fig. 2 is a side elevation.

I claim:

The ornamental design for a toy bank, as shown.

LOUIS KRAJESKI.
